UNITED STATES PATENT OFFICE.

HENRY CRUSE, OF HYDE, ENGLAND.

STEAM SUPERHEATER.

Application filed May 12, 1925, Serial No. 29,742, and in Great Britain May 19, 1924.

This invention relates to improvements in steam superheaters and whilst it has particular reference to superheater elements for use in the smoke tubes of locomotives and marine 5 and the like boilers may nevertheless be used for superheating steam in other services where its application would be useful and effective, the object being to provide a superheater element or elements which will give 10 increased efficiency whilst at the same time being simple in construction.

A further object is to provide improved means for coupling up the superheater elements either directly to each other and/or to 15 the headers or distributor and collector for wet and superheated steam.

My invention has for its object to provide an improved form of superheater element or tube primarily for use in the smoke tubes of 20 locomotive, marine and the like, boilers.

In its simplest form the superheater element according to the invention consists of two tubes formed into two semi-circular or substantially semi-circular tubes closed at 25 their longitudinal facing edges and ends and each embodying a comparatively thin semi-annular steam race or space between its inner and outer walls; a central through passage 30 for heating gases formed by joining the tubes together at the longitudinal edges and ends; passages for connecting the two steam races or spaces and for returning the steam to the outer ends and coupling means for conducting the steam from one element to the element 35 next adjacent to it or to a coupling element or header common to a series of tube elements which header elements in turn are connected to the wet and superheated steam headers or distributor and collector.

40 My invention will be fully described with reference to the accompanying drawings in which,

Fig. 1, is a longitudinal sectional elevation of one of the tube elements,

Fig. 2, elevation of same showing the welding of the semi-circular tubes at local points,

Fig. 3, cross section on line 3-3 of Fig. 1,

Fig. 4, cross section on line 4-4 of Fig. 1,

Fig. 5, fragmentary longitudinal section to an enlarged scale showing one form of construction of the inner end of the tube,

Fig. 6, longitudinal section to an enlarged scale showing a series of tube elements arranged in the smoke tubes of a locomotive or marine or like boiler and means for connect-

ing their outer ends together and to the headers or the like,

Fig. 7, end elevation, partly in section, on line 7-7 of Fig. 6, showing the tube connection device or header and

Figs. 8, 9 and 10 sectional side elevations and section respectively showing different means for coupling two tube elements together.

Fig. 11 is a fragmentary view on an enlarged scale showing another form of construction of the inner end of the tube.

In carrying out my invention and referring particularly to Figs. 1 to 4 each superheater element consists of two semi-circular tubes 70 a and a' each a half tube containing a comparatively thin semi-annular race or steam space b between its inner wall c and outer wall d . In the truly semi-circular form this space would have concentric sectional walls 75 as shown in Figs. 3 and 4, though on the other hand I may depart from such true form by pressing one of the walls nearer to the other at its central cross sectional point, or both walls may be somewhat distorted. The longitudinal edges e of the semi-circular tubes are closed and may be flat as shown or of semi-circular formation and in either case be welded together at local points f or throughout the full length of the joining surfaces 80 though, on the other hand, I may secure them together with other convenient means such as clips or the like. The tubes so connected are placed in position within the fire or smoke tubes g Figs. 6 and 7, so as to be concentric 85 therewith leaving an annular space or passage h between the outer wall of the superheater tube and the inner wall of the smoke tube for the passage of a portion of the heating gases from the firebox; and a cylindrical 90 or substantially cylindrical central passage i formed inside the inner walls of the superheater tube for the passage of the remainder of the heating gases to the smoke box.

At the inner end of that end of the element 100 inside the fire or smoke tube the two semi-circular tubes forming the element may be connected together (Fig. 11) by a short annular tube 12 closed at one end and open at the other to embrace the walls of the two semi-circular tubes and be suitably screwed and/or welded thereto, or the annular connection tube 105 may consist of two short tubes of different diameter closed by welding or other means at their outer ends. Other devices may be used 110

but in all cases designed to form an annular connection for the semi-circular tubes which allows for the passage of steam from the race or steam space of one half tube to that of the other in opposite directions.

In another form I may return the steam stream from the space *b* in one semi-circular tube to the other at the inner end by means of an annular chamber by cutting away the edges or webs *e* for a short distance from the extreme end as at *f'*, and closing the space by a ring *m* fitting the space and preferably welded in.

I may attach a gas shield *n* to the ring by screws *n'* or weld such shield to the ring. Or the ring and shield may be integral and be welded to the tubes. I may form the outer end of the shield *n* with a somewhat sharp end as shown to more efficiently divide the heating gases into streams, one to pass through the annular space *h* between the superheater tube element *a* and the smoke tube *g* and the other stream to pass through the centre space *i* of the superheater tube element.

In the preferred form for connecting a series of tubes *a* with each other I employ a chamber or header *o* as shown in Figs. 6 and 7 common to them all into which the outer walls *d* of the outer ends of the tubes *a* may be shrunk or otherwise tightly fitted, such outer walls being cut away at *p* to form passages for the steam in the process of superheating. When not shrunk into the chamber *o* each tube element may be connected to such chamber by providing it with a fixed collar *q* having a tubular ball ended neck *r* fitting in a correspondingly shaped groove in the inner wall of the chamber and a tubular nut *s* having a ball ended neck of the character referred to, such nut being tightened up on the screw-threaded end of the tube. The annular space at such end is closed in by a ring *t* welded into the tube. The arrangement permits each tube to be separately and readily removed from its position in the chamber or header *o*. The latter is coupled at one end to the wet steam header or distributor *u* and at the other end to the superheated steam header or collector *v* by any suitable device as for instance by sockets *w*, the outer ends of which are provided with cap nuts *x*.

In the aforesaid arrangement the steam to be superheated passes from the wet steam header first into the chamber *o*, then along the semi-annular space of one half tube to the inner end and thence through the semi-annular space of the other half tube into the chamber *o* and so on throughout the whole of the tubes of the series to the superheated steam header. The heated gases of the combustion pass through the annular space *h* between the smoke tube *g* and superheater element *a*, *a'* and through the central space *i* in the latter.

From the foregoing arrangement it will be seen that when the element is fitted into the

flue tube two clear gas runs are formed permitting of free travel of the heating gases from firebox to smoke box.

In the annulus *h* the dual function of the gases is to heat the boiler water through the flue tube *a* and to superheat the steam in the races *b* of the element; the major portion of the heat transmitted going through the flue tube to the boiler water. In the central core or area *i* the sole function of the gases is to superheat the steam travelling through the surrounding races from end to end, to and fro of the element. This gas core thus becomes a fire-tube affected solely to the efficient superheating of the steam travelling at high velocity around it. The element *a*, *a'* is held in the flue tube *g* by short strips or lugs 13 suitably placed.

In Figs. 8, 9, and 10 I have indicated by way of example other means to those described in connection with Figs. 6 and 7 for coupling up the superheater elements. Thus in Fig. 8, each element *a*, *a'* has short radiating tubes 2 internally screw-threaded coupled by short tubes 3 externally screw-threaded. In Fig. 9, the short tubes 2 are coupled by flanged tubes 4, the flanges of which are bolted together. In Fig. 10 the short tubes 2 are externally screw-threaded and each is fitted with a tubular sleeve 5 internally screw-threaded, one sleeve being provided with an annular groove 6 and the other with a projecting tongue 7 to interengage. A packing washer 8 is placed in the groove 6. The tongued sleeve is externally screw-threaded to receive an internally screw-threaded union 9 having an internally-projecting flange 10 bearing on a shoulder 11 of the upper sleeve 5. The union 9 is screwed up to form a tight joint between the sleeves 5.

I do not confine myself to the detail arrangement hereinbefore described for connecting the superheater elements to each other as these may be varied without departing from the essential characteristics of my invention.

I would have it understood that I may arrange two or more superheater tube elements within a single smoke or other tube instead of employing one element only.

What I claim as my invention and desire to secure by Letters Patent is:—

1. A superheater element comprising two substantially semi-annular tubes connected at their longitudinal edges to form a tubular passage for the flow of hot gases, openings provided on the outer walls of each near one end for admission of steam to one and discharge of steam from the other, means closing each semi-annular tube at this end, and means at the other end of said tubes forming an annular passage connecting the two tubes to enable steam flowing up one tube to flow down the other tube in contrary direction.

2. A plurality of aligned superheater ele-

ments each constructed from two substantially semi-annular tubes connected at their longitudinal edges to form a tubular passage for the flow of hot gases, openings provided 5 on the outer walls of each tube near one end for admission of steam to one and discharge of steam from the other, means closing each semi-annular tube at this end, means at the other end of said tubes forming an annular 10 passage connecting the two tubes to enable steam flowing up one tube to flow down the other tube in contrary direction, in combination with a pair of headers and means to connect the superheater elements seriatim to each 15 other and the first and last of them to the two headers respectively.

3. A plurality of superheater elements each constructed according to claim 1 in combination with a row of aligned flues into which the 20 elements extend; a tubular member located directly in front of said row of flues through which said elements extend transversely, the openings on the outer walls of the semi-annular tubes communicating with the interior of 25 the tubular member, the arrangement being such that each element interrupts communication of the part of the interior of the tubular member on one side of the superheater element with that on the other except by way of 30 the two semi-annular tubes and the annular connecting passage at their further ends.

4. The combination of an element according to claim 1 with an elongated hollow body whose interior width is slightly less than the 35 exterior diameter of the element, the hollow body having an aperture through it through which the element extends, the openings on the outer walls of the semi-annular tubes opening into the hollow member in opposite 40 directions, a collar fixed to said element and

bearing against said hollow body to make a tight joint, and a nut screwed on the element, said nut bearing against the body and making a tight joint.

5. A superheater element comprising two 45 substantially semi-annular tubes connected at their longitudinal edges to form a tubular passage for the flow of hot gases, two 50 openings on opposite sides in the outer walls near one end for the admission and discharge of steam, means closing the semi-annular tubes at this end, a short annular cap piece connecting said semi-annular tubes at the other end, the annular space of said cap piece being closed at one end and communicating at 55 the other end with the inner space of the two semi-annular tubes, the central passage of the cap piece communicating with the tubular passage between said semi-annular tubes.

6. A superheater element comprising two 60 tubes each having a substantially semi-annular closed passage therein and presenting a semi-circular trough, said troughs forming a central circular flue when the tubes are joined together, each of said tubes having means adjacent one end for the admission of steam to one and the discharge of steam from the other tube, means closing each tube at this end, and an annular member at the other end connected to both of said tubes to close the same, the 65 70 said tubes and member being constructed and arranged to establish a communication between the tubes at this other end so that steam can flow from the admission means in one direction through one tube and back to the discharge means through the other tube.

In testimony whereof I have hereunto set my hand.

HENRY CRUSE.
